INVENTOR:

Eugene Frank Schoell.

By Louis M. Schmidt

Atty.

UNITED STATES PATENT OFFICE.

EUGENE F. SCHOELL, OF NEW BRITAIN, CONNECTICUT.

CURTAIN-FASTENER.

1,312,138.

Specification of Letters Patent. Patented Aug. 5, 1919.

Application filed May 12, 1917, Serial No. 168,194.

Renewed December 26, 1918. Serial No. 268,414.

To all whom it may concern:

Be it known that I, EUGENE FRANK SCHOELL, a citizen of the United States, residing at New Britain, in the county of 5 Hartford and State of Connecticut, have invented certain new and useful Improvements in Curtain-Fasteners, of which the following is a specification.

My invention relates to improvements in 10 curtain fasteners, of the type for holding curtains of automobiles and other vehicles and the object of my improvement is to produce a curtain fastener in which the stud member is formed of a pair of coöoperating 15 spring members that are held in place by the resiliency of the material of which it is made and that is made of a single piece of strip, sheet material.

In the accompanying drawing:—
20 Figure 1 is a plan view of my improved curtain fastener with adjacent parts of curtain to which the same is applied.

Fig. 2 is a similar view on an enlarged scale of the curtain fastener shown in Fig. 1.

25 Fig. 3 is a similar view of the eye or socket member.

Fig. 4 is a similar view of the stud member.

Fig. 5 is a plan view of the blank for the 30 stud member.

Fig. 6 is a sectional view on the line $\alpha\alpha$ of Fig. 1.

Fig. 7 is a similar view with the opposing arms of the stud members in the closed 35 position for being released by engagement with the socket member.

My improved curtain fastener comprises a socket member 10 for being secured to one 40 of the curtains or other devices to be fastened together, such as the curtain 11, and provided with a hole 12 in the middle portion for receiving the other member of the curtain fastener, and the said other member 13 is in the form of a stud member that is 45 secured to the framework and the same is provided with means for engaging with the hole 12 in the socket member 10 to be described.

The socket member 10 is composed of a 50 pair of mating plates for being positioned, one on each side of the curtain 11, and held together by lugs or prongs 14 that are integral with one of the plates, extend through the material of the curtain 11, and

are bent over against the outer face of the 55 other plate.

As shown, the outer plate 15 is positioned on the outer face of the curtain 11, has a set of four lugs or prongs 16 distributed around the periphery that penetrate the 60 material of the curtain 11, and has the hole 12 at the middle. The inner plate 17 is positioned at the rear or inner face of the curtain 11, has notches 18 in the peripheral 65 edge that register with and receive the prongs 14, and has an opening 19 in the middle portion.

The ends of the prongs 14 are bent over against the inner face of the inner plate 17.

The plates 15 and 17 are made of sheet 70 material and the hole 12 in the outer plate 15 serves as the socket member proper, the opposed edge portions 20 on two sides serving as the engaging or locking members for coöperating with the stud member 13. The 75 opening 19 in the inner plate 17 is appreciably larger than the socket hole 12 in the outer plate 15, suitably to provide clearance for the stud member 13.

The stud member 13 is formed from a 80 single piece of sheet material in strip form, the middle portion 21 being straight for an appreciable length to form the base, the material being bent back by a return bend 22 at the ends of the base 21 and extending along inwardly to provide reinforcing members 23 for the end portions of the base 21 and at the inner, opposed ends of the reinforcing members 23 are outwardly 85 extending branches 24 that are directed 90 generally at a right angle to the base 21 and that serve as spring arms and coöperate suitably to serve as the stud proper, in engagement with the socket member 10.

The spring arms 24 are positioned in 95 spaced relation so as to be a snug fit in the socket hole 12 in the socket member 10, and are provided with engaging members 25 for engaging with the opposed edge portions 20 of the socket hole 12.

The said engaging members 25 are in 100 the form of lugs formed integral with the arms by slitting the material at the lower edge 26 of the lug and indenting the material outwardly above the slit. These 105 lugs therefore are rigid *per se*. Thus the lugs 25 have an abrupt lower edge 26, suitable for locking against the coöperating

edge portions 20 of the socket hole 12, and the outer faces 27 are inclined, suitably to provide converging sliding surfaces that facilitate bringing the parts into engagement.

The base 21 is provided with holes 28 for holding screws by which the stud member 13 is secured to the woodwork or other supporting device.

10 The parts are brought into engaging position by slipping the socket member over the arms of the stud member, the edges of the socket hole engaging with the lugs 25 and forcing the arms 24 together momentarily, and after the socket member is brought below the holding edges 26 the arms will spring back to the holding position.

For releasing the parts the ends of the arms 24 are squeezed together until the 20 socket member can be slipped over the lugs.

As shown the arms 24 are appreciably concaved and the active edges 20 of the socket hole 12 are formed to correspond. It is understood other shapes for these parts 25 may be used than those shown.

I claim as my invention:—

1. A curtain fastener, comprising a socket member of sheet material, having means for securing it to a curtain and provided with 30 a stud-engaging hole, and a stud member formed of a single piece of strip sheet material, having a middle portion adapted to serve as a base, and reinforcing end portions overlying the base and extending toward one another and terminating in a 35

Copies of this patent may be obtained for five cents each, by addressing the "Commissioner of Patents, Washington, D. C."

pair of coöperating spring arms arranged in spaced relation and adapted to be entered in the socket hole, each arm provided with an outwardly directed lug having an abrupt lower edge to engage the edge portion of the socket hole.

2. In a curtain fastener, a socket member having an opening for receiving a stud member, and a stud member for coöperating with said socket member, said stud member 45 formed of a single piece of strip sheet material with its middle portion serving as a base and having reinforcing end portions formed by return bends at the ends of said base, the ends of said return bends extending outwardly in parallelism and in spaced relation and supported by the return bends, said ends provided with coöperating outwardly directed rigid lugs for engaging the socket member.

3. A stud member for curtain fasteners, formed of a single piece of strip sheet material, and comprising a socket-engaging portion in the form of a pair of spring arms arranged in spaced relation and having lugs 60 on their outer faces made with abrupt locking edges, a base adapted to be engaged with a support for the stud member, and connecting parts interposed between said base and arms and uniting them.

EUGENE F. SCHOELL.
